HIS ATTORNEY.

UNITED STATES PATENT OFFICE.

AUGUST BLOMQUIST, OF CHICAGO, ILLINOIS.

HOT-WATER ATTACHMENT FOR GAS-STOVES.

1,285,001.

Specification of Letters Patent. Patented Nov. 19, 1918.

Application filed January 22, 1917. Serial No. 143,720.

To all whom it may concern:

Be it known that I, AUGUST BLOMQUIST, a former subject of the Czar of Russia, have declared my intention of becoming a citizen 5 of the United States, a resident of the city of Chicago, county of Cook, and State of Illinois, have invented certain new and useful Improvements in Hot-Water Attachments for Gas-Stoves, of which the following is a specification.

My invention relates to improvements in hot water attachments for gas stoves and has for its object the provision of an improved construction of this character, which is 15 highly efficient in use.

The invention consists in the combinations and arrangements of parts hereinafter described and claimed.

The invention will be best understood by 20 reference to the accompanying drawings forming a part of this specification, and in which,

Figure 1 is a top plan view of a gas stove burner equipped with an attachment, embodying my invention,

Fig. 2 is a section taken on line 2—2 of Fig. 1, and

Fig. 3 is a section taken on line 3—3 of Fig. 1.

30 The preferred form of construction as illustrated in the drawings comprises a gas burner consisting of an outer annular gas chamber 4 and an inner central circular gas chamber 5, the gas chamber 4 being provided 35 in its top with two sets of burner openings 7 arranged in the form of concentric rings, and the chamber 5 being provided with a set of burner openings 8 arranged in the form of a ring. The gas chamber 4 is supplied 40 with gas through a mixing passage or chamber 9 communicating with a gas supply pipe 10 through a valve 11, as indicated. A branch pipe 12 leads from the pipe 10 and is provided with branches 13, 14 and 15.

45 The branch 13 leads to a passage opening in the outer ring of burner openings 7, the branch 14 leads to a passage opening in the inner ring of openings 7 and the branch 15 leads to a passage opening centrally in the ring of openings 8, said passages serving to 50 preserve pilot lights for lighting the gas escaping through said burner openings when valve 11 is opened, as will be readily understood.

55 An outer annular water heating chamber 16 is formed integrally on top of the burner

outside of and surrounding the burner openings. An intermediate annular water heating chamber 17 is formed integrally on top of the gas chamber 4 between the rings of 60 burner openings 7 in the top thereof, and an inner annular water heating chamber 18 is arranged above and between the chambers 4 and 5, as shown. At one side the chambers 16, 17 and 18 are connected together by 65 means of passages 19 and 20 and at the opposite side the chambers 17 and 18 are connected by means of a passage 21. At said opposite side the chamber 17 is formed with an outlet passage or pipe 22, and the outer 70 chamber 16 is provided with a depression 23 passing under the pipe 22 and provided with an inlet pipe or passage 24 for admitting water to said water chambers.

By this arrangement, it will be observed, 75 that the water passing through the device will first pass through the outer chamber 16 and be partially heated therein, said outer chamber also serving to partially confine the flame and heat from the outer ring of burner openings 7. The water passing through the outer chamber 16 then passes into the inner chambers 17 and 18 and is thoroughly and intensely heated therein, the flame and heat from the inner set of burner openings 7 passing 80 between said chambers and the flame and heat from the central burner chamber 5 passing through the space inclosed by the chamber 18, thus efficiently and intensely heating the water in said chambers. The heated 85 water is drawn through the passage 22, thus compelling a complete and efficient circulation of the water through the device.

While I have illustrated and described the preferred form of construction for carrying 95 my invention into effect, this is capable of variation and modification without departing from the spirit of the invention. I, therefore, do not wish to be limited to the precise details of construction set forth, but 100 desire to avail myself of such variations and modifications as come within the scope of the appended claims.

Having described my invention what I 105 claim as new and desire to secure by Letters Patent is:

1. A device of the class described comprising a burner consisting of an outer annular burner chamber having burner openings in the top thereof arranged in two annular 110 rings, and an inner central circular burner chamber having burner openings in the top

- thereof arranged in the form of a ring; an annular water chamber formed on the top of said burner surrounding the same; a second annular water chamber formed on the top of 5 said outer annular burner chamber between the rings of burner openings therein; an inner annular water chamber located above and between said outer annular burner chamber and said inner central burner chamber; connections between said water chambers at one side; a connection between the 10 inner and the intermediate water chambers at the opposite side; an outlet connection with said intermediate chamber at said opposite side; and an inlet connection with 15 said outer annular water chamber at said opposite side, substantially as described.
2. A device of the class described comprising a burner consisting of an outer annular burner chamber having burner openings in the top thereof arranged in two annular rings, and an inner central circular burner chamber having burner openings in the top thereof arranged in the form of a ring; an 20 annular water chamber formed on the top of said burner surrounding the same; a sec-
- 25

ond annular water chamber formed on the top of said outer annular burner chamber between the rings of burner openings therein; an inner annular water chamber located 30 above and between said outer annular burner chamber and said inner central burner chamber; connections between said water chambers at one side; a connection between the inner and the intermediate water chambers 35 at the opposite side; an outlet connection with said intermediate chamber at said opposite side; an inlet connection with said outer annular water chamber at said opposite side; a valve and a pipe supplying gas 40 to said outer annular gas chamber; and a branch gas pipe leading from said valve and having branches opening in operative relation with the different sets of burner openings, substantially as described. 45

In testimony whereof I have signed my name to this specification in the presence of two subscribing witnesses.

AUGUST BLOMQUIST.
